Specification for Design.

Patented Feb. 5, 1918.

Application filed October 15, 1914. Serial No. 866,866. Term of patent 7 years.

To all whom it may concern:

Be it known that I, AGNES B. CASCADEN, a citizen of the United States, residing in the city and county of San Francisco, State of California (whose post-office address is Golden West Hotel,) have invented a new, original, and ornamental Design for Badges, of which the following is a specification, reference being had to the accompanying drawings, forming part thereof.

In the drawings Figure 1 is a perspective of a badge showing my new design.

Fig. 2 is a rear elevation showing the reverse side of the emblem.

I claim:

The ornamental design for a badge as shown.

In testimony whereof, I have hereunto set my hand this thirtieth day of September 1914.

AGNES B. CASCADEN.
